UNITED STATES PATENT OFFICE

ARTHUR LOLLO, OF BROOKLYN, NEW YORK

DESIGN FOR A CONDIMENTS HOLDER

Application filed November 12, 1930. Serial No. 37,628. Term of patent 14 years.

To all whom it may concern:

Be it known that I, ARTHUR LOLLO, a citizen of the United States, residing at Brooklyn, in the county of Kings, State of New York, have invented a new, original, and ornamental Design for a Condiment Holder, of which the following is a specification, reference being had to the accompanying drawings, forming part thereof.

In the drawings:—

Fig. 1 is a top plan view of the condiment holder showing my new design, and

Fig. 2 is a front elevation of the same.

I claim:

The ornamental design for a condiment holder, as shown.

ARTHUR LOLLO.
